UNITED STATES PATENT OFFICE.

JOHN H. CLAPPISON, OF EASTON, PENNSYLVANIA.

DESIGN FOR A SHOE-UPPER.

SPECIFICATION forming part of Design No. 28,277, dated February 8, 1898.

Application filed December 30, 1897. Serial No. 664,739. Term of patent 14 years.

To all whom it may concern:

Be it known that I, JOHN H. CLAPPISON, a citizen of the United States, residing at Easton, in the county of Northampton and State 5 of Pennsylvania, have invented and produced a new and original Design for a Shoe-Upper; and I do declare the following to be a full, clear, and exact description of the same, reference being had to the accompanying drawing, forming a part thereof.

This invention relates to a novel design for shoe - uppers wherein a peculiar cut of the material is presented, the shape or contour of which when viewed in plan presents inner and 5 outer curves as well as oblique and straight lines.

In the drawing the figure represents a plan view of my novel design for a shoe-upper, this view only being deemed necessary to fully 5 illustrate my design.

The leading features of my design consist in the outer contour, starting at the point *a*, presenting a straight line to the point *b*, and then slightly curves inwardly to a point *c* and 5 continues with an outward curve to the point *d*, rounding with an outward curve between the points *d* and *e*. From this point *e* the shape of the upper is similar to that just described, being an outward curve from the point *e* to the point *f*, slightly inwardly curved between the points *f* and *g* and a straight line from *g* to *h*. From the point *a* an outwardly-curved line extends to a point *j*, where the same line starts to curve inwardly and 5 terminates at the point *a'*. From the point *a'* a straight line extends to a point *z* and then takes an oblique direction in a straight

course to a point *y*, whence it extends in a straight line to a point *x*, thence in an oblique direction to a point *w*, and from this point *w* 40 the straight line extends to the point *v*. From this point *v* a deep curve extends to a point *u*, from which latter point a slightly outwardly curved line extends to the point *t*, where it continues in a gradual inner curve to the 45 point *s*. Starting at this point *s* a similar inner gradual curve extends to the point *r*, where a slightly outwardly curved portion extends to a point *q*, and between this point and the point *p* a deep inner curve is presented. From the point *p* a straight line extends to the point *o*, and from which point *o* 50 extends an oblique line to the point *n*, and from said point *n* a straight line extends to the point *m*, from which latter point an oblique line extends to the point *l* and continues 55 in a straight line to a point *k*. From this point *k* an inwardly-curved line extends to the point *i*, and continues from said point *i* in an outward curve to the point *h*. 60

It will be seen that my design presents two portions of the upper having duplicate straight lines and curves, and at the same time the two portions are not divided or separated from one another. 65

What I claim is—

The design for a shoe-upper, herein shown and described.

In testimony whereof I affix my signature in presence of two witnesses.

JOHN H. CLAPPISON.
